ELECTROMAGNETIC OVERLOAD CIRCUIT
BREAKER

Wilhelm Leyhausen, Nuremberg, Germany

Application December 1, 1933, Serial No. 700,579
In Germany October 18, 1933

10 Claims. (Cl. 200—89)

This invention relates to an electro-magnetic overload circuit breaker in which the circuit is broken between the end faces of two magnetic coils, the spark gap being formed by fire-proof partitions which separate the contacts from the coils and protect against flashing over of the breaking spark. Constructions of such circuit breakers are already known in which the release is effected by an armature which is attracted by the two separate magnet coils. The attracting force of the magnet coils is at the same time extremely weak, so that the release can only be caused at a multiple of the nominal current strength.

15 This objection is overcome by the invention in that, at least one of the magnet coils has a plunger which communicates with the releasing device on the side remote from the magnet coils. Thus, not only a better moment of attraction 20 of the magnet coils and a more rapid operation is obtained, but it also enables the blowing effect of the coil to be increased in that the coil is provided with a rigid magnetic connection, a yoke or frame, for employing which a separate 25 switching magnet was hitherto required, whereby the device was rendered complicated and expensive.

Two embodiments of the invention are illustrated by way of example in the accompanying 30 drawing in which:—

Fig. 1 shows the circuit breaker partly in side elevation and partly in section.

Fig. 2 is a similar view of a modified form of construction.

35 Fig. 3 is a diagrammatic view of a switching mechanism necessary for the circuit breakers illustrated in Figs. 1 and 2.

In Fig. 1 contacts *a* and *b* are arranged between magnet coils *c* and *d*, the outer poles of 40 which are magnetically connected to an iron strap *e*. The contacts are separated from the magnet coils by fireproof partitions *e'* and *d'*. The coil *c* has a fixed magnet core whereas the coil *d* is provided with a plunger *f*. This latter 45 is connected to a bell-crank lever *g* the free end of which can act upon the switching mechanism *h*. The connection between the switching mechanism and the contacts has been omitted 50 from the drawing for the sake of clearness. In the switching in position the contacts *a* and *b* touch one another. If the current exceeds a certain strength, the plunger *f* is attracted causing the bell crank lever *g* to strike against the 55 switching mechanisms whereby the switch is

moved into the cutting out position. The arc forming between the contacts is extinguished by the magnet coils. By fitting a spring counter-acting the force of attraction of the coil *d* on the plunger *f* the strength of the switching out current can be regulated in known manner.

In Fig. 2 the iron strap *e* is extended to form an iron frame *r*, which serves at the same time for fixing the system on a base *s*. Contrary to the form of construction shown in Fig. 1 the bell crank lever *g'* in Fig. 2 is made of iron and one of its arms, to which the plunger *f* is fixed, forms a part of the frame *r*. In other respects the operation is the same as that of the form of construction shown in Fig. 1. The frame *r* 10 may be entirely closed and the bell-crank lever *g'* and plunger *f* constructed as illustrated in Fig. 1.

The peculiar arrangement of the coils, contacts and magnetic release requires a special 20 switching mechanism. An advantageous form of construction is shown in Fig. 3 on a switch with two contacts.

The contacts *a* and *b* are resiliently mounted on the base *s* and a contact bridge *u* is arranged 25 opposite the contacts on a switch bar *t*.

A toggle lever system consists of a bell crank lever *k*, *p* of a lever *l* pivotally mounted on a rigid pin *n*, of two links *h*, *i* forming a toggle lever and pivotally connected with each other 30 by a pivot pin *o*, the lever arm *h* connected with the arm *k* of the bell crank lever by a pivot pin *m'* and the lever *i* with the lever *l* by a pivot pin *n'*. The arm *p* of the bell crank lever is pivoted on a pivot pin *n'* fixed on the switch 35 bar *t* the lever being pivotally mounted on the pivot pin *o*. The arm *p* of the bell crank lever is influenced by a spring *q* and pressed against an abutment *w*.

If a switch lever *z* is swung in clockwise direction, a pin *x* eccentrically mounted on the switch lever *z* acts on the lever *l* and brings the lever system into the switching in position shown in dotted lines.

During this movement the pivot pin *o* of the 45 toggle lever *h*, *i* moves in a straight line and always at the same distance from the bell crank lever *g* effecting the release, so that it always strikes against the lever *h* in the same position and with the same force in the event of shorting or overload. The device therefore forms a 50 free release with an ideal manner of operation, no matter whether the releasing lever is electro-magnetically or thermally controlled. In the 55

present instance the device is of particular importance because the movement of the releasing lever can be limited to the smallest size so that the switching speed is increased and the magnet parts can be placed in the most favorable position from the outset.

In order to attain the rectilineal movement of the pivot pin *o*, the levers *k* and *l* are of the same length and also the two links *h* and *i* of the toggle lever. During the switching in movement the pivot pin *m'* must therefore approach and move away from the engaging surface of the releasing lever *g* in the same proportion as the pivot pin *n'* moves away from and approaches the same. Thus, by differently dimensioning and mounting the levers *k* and *l*, the device can be constructed so that the pivot pin *o*, during the switching in operation changes its distance from the releasing lever *g* to a predetermined extent, being desirable in certain instances.

The bell crank lever *k*, *p* is also of particular importance for the device. By suitably shaping and arranging the same the horizontal movement of the toggle lever *h*, *i* can impart a vertical movement to the switch bar *t*, so that the switch may be of compact construction and space and material is saved.

The automatic breaking of the circuit is effected as follows. The device is shown in circuit closing position by dotted lines in Fig. 3. If a short-circuit or an overload occurs, the lever *g* presses against the pivot pin *o*. The toggle lever *h*, *i* is thereby bent, and the bell crank lever *k*, *p* swings under the pressure of spring *q*, thereby lifting the switch bar *t* and causing contact bridge *u* to lift from contacts *a* and *b* and break the circuit. At the same moment the coil *d* is de-energized so that the lever *g* may return to its position of rest. The toggle lever *h*, *i* may hence return to its alined position under the force of its own weight, so that the position of the individual parts is now that shown in Fig. 3 in straight lines, that is, in open circuit position.

This is permitted because the resetting lever *z* is normally in position shown by full lines and the arm *b* can thus freely swing to the right and offers no substantial resistance to the dropping of the pivot pin *o*. With the parts in the full line position, it is merely necessary to move the resetting lever *z* to the dotted line position whereupon the toggle will push the lever arm *k* to the left and cause the lever arm *p* to swing downwardly to depress the bar *t* and bridging contact *u* so that the latter again bridges the contacts *a* and *b*. The resetting lever *z* may now be swung to full line position, thus leaving all parts ready for the next operation.

Both coils instead of only one may be provided with plungers if a stronger force is necessary for the releasing. The magnet core of the coils may likewise be divided and one part thereof be fixed whereas the other part forms the plunger.

I claim:—

1. In an electro-magnetic overload circuit breaker, magnet coils, contacts between the end faces of the coils, a plunger in one of the magnet coils, a releasing mechanism for opening the contacts, a transfer means between the plunger and the release mechanism, said transfer means including a toggle, a pivoted arm linked to one end of the toggle, a bell crank lever connected to the other end of the toggle, and a switch bar fastened to the free end of the said bell crank lever and displaceable crosswise of the axis of the coils.
2. In an electro-magnetic overload circuit

breaker, magnet coils, contacts between the end faces of said coils, a release mechanism consisting of a toggle, an electro-magnetically controlled bell crank for breaking said toggle, one arm of said bell crank lever being connected to be actuated by energization of one of said magnets, a pivoted arm equal in length to the other arm of said bell crank, said pivoted arm and said other arm of said bell crank being connected together by means of said toggle, whereby the joint of 10 the toggle is uniformly distant from the electro-magnetically controlled bell crank lever in all positions of the toggle while its arms are in alinement.

3. In an overload circuit breaker, a pair of axially alined and spaced magnet windings, circuit contacts between the adjacent ends of the windings, one of said contacts being fixed and a second of said contacts being movable transversely of the field between said windings, a frame magnetically connecting the remote ends of said windings, a lever having one end pivoted to the frame and projecting upwardly therefrom, a bell crank lever pivoted at its angle to said frame and having a depending arm, a pair of pivotally jointed links constituting a toggle, said toggle having its ends connected respectively to the first lever and the depending arms of the bell crank lever, a lift rod pivoted to the remaining arm of the bell crank lever and carrying the movable contact, a spring urging said bell crank lever to move the lift rod to open circuit position, and means actuated by energization of said windings to engage and flex the toggle at its joint.

4. In an overload circuit breaker, a pair of axially alined and spaced magnet windings, circuit contacts between the adjacent ends of the windings, one of said contacts being fixed and a second of said contacts being movable transversely of the field between said windings, a frame magnetically connecting the remote ends of said windings, a lever having one end pivoted to the frame and projecting upwardly therefrom, a bell crank lever pivoted at its angle to said frame and having a depending arm, a pair of pivotally jointed links constituting a toggle, said toggle having its ends connected respectively to the first lever and the depending arms of the bell crank lever, a lift rod pivoted to the remaining arm of the bell crank lever and carrying the movable contact, a spring urging said bell crank lever to move the lift rod to open circuit position, a second bell crank lever pivoted to said frame and having one arm below the joint of the toggle and its other arm depending across the remote end of one of said windings, and a magnetic core in the last mentioned winding and connected to the depending arm of the second bell crank lever.

5. In an overload circuit breaker, a pair of axially alined and spaced magnet windings, circuit contacts between the adjacent ends of the windings, one of said contacts being fixed and a second of said contacts being movable transversely of the field between said windings, a frame magnetically connecting the remote ends of said windings, a lever having one end pivoted to the frame and projecting upwardly therefrom, a bell crank lever pivoted at its angle to said frame and having a depending arm, a pair of pivotally jointed links constituting a toggle, said toggle having its ends connected respectively to the first lever and the depending arms of the bell crank lever, a lift rod pivoted to the remaining arm of the bell crank lever and carrying the movable contact, a spring urging said bell crank

lever to move the lift rod to open circuit position, and means actuated by energization of said windings to engage and flex the toggle at its joint, said links being of equal length and the lever arms to which the ends of the toggle is connected being also of equal length.

5. In an overload circuit breaker, a pair of axially alined and spaced magnet windings, circuit contacts between the adjacent ends of the windings, one of said contacts being fixed and a second of said contacts being movable transversely of the field between said windings, a frame magnetically connecting the remote ends of said windings, a lever having one end pivoted to the frame and projecting upwardly therefrom, a bell crank lever pivoted at its angle to said frame and having a depending arm, a pair of pivotally jointed links constituting a toggle, said toggle having its ends connected respectively to the first lever and the depending arms of the bell crank lever, a lift rod pivoted to the remaining arm of the bell crank lever and carrying the movable contact, a spring urging said bell crank lever to move the lift rod to open circuit position, a second bell crank lever pivoted to said frame and having one arm below the joint of the toggle and its other arm depending across the remote end of one of said windings, a magnetic core in the last mentioned winding and connected to the depending arm of the second bell crank lever, and a resetting lever pivoted to the frame and provided with a pin for engaging the first lever to move the same to circuit closing position.

6. In an overload circuit breaker, a pair of axially alined and spaced magnet windings, circuit contacts between the adjacent ends of the windings, one of said contacts being fixed and a second of said contacts being movable transversely of the field between said windings, a frame magnetically connecting the remote ends of said windings, a lever having one end pivoted to the frame and projecting upwardly therefrom, a bell crank lever pivoted at its angle to said frame and having a depending arm, a pair of pivotally jointed links constituting a toggle, said toggle having its ends connected respectively to the first lever and the depending arms of the bell crank lever, a lift rod pivoted to the remaining arm of the bell crank lever and carrying the movable contact, a spring urging said bell crank lever to move the lift rod to open circuit position, a second bell crank lever pivoted to said frame and having one arm below the joint of the toggle and its other arm depending across the remote end of one of said windings, a magnetic core in the last mentioned winding and connected to the depending arm of the second bell crank lever, and a resetting lever pivoted to the frame and provided with a pin for engaging the first lever to move the same to circuit closing position.

7. In an overload circuit breaker, a pair of axially alined and spaced magnet windings, circuit contacts between the adjacent ends of the windings, one of said contacts being fixed and a second of said contacts being movable transversely of the field between said windings, a frame magnetically connecting the remote ends of said windings, a lever having one end pivoted to the frame and projecting upwardly therefrom, a bell crank lever pivoted at its angle to said frame and having a depending arm, a pair of pivotally jointed links constituting a toggle, said toggle having its ends connected respectively to the first lever and the depending arms of the bell crank lever, a lift rod pivoted to the remaining arm of the bell crank lever, and carrying the movable contact, a spring urging said bell crank lever to move the lift rod to open circuit position, means actuated by energization of said windings to engage and flex the toggle at its joint, and a resetting lever pivoted to the frame and provided with a pin for engaging the first lever to move the same to circuit closing position.

8. In an overload circuit breaker, a pair of axially alined and spaced magnet windings, circuit contacts between the adjacent ends of the windings, one of said contacts being fixed and a second of said contacts being movable transversely of the field between said windings, a frame magnetically connecting the remote ends of said windings, a lever having one end pivoted to the frame and projecting upwardly therefrom, a bell crank pivoted at its angle to said frame and having a depending arm, a pair of pivotally jointed links constituting a toggle, said toggle having its ends connected respectively to

the first lever and the depending arms of the bell crank lever, a lift rod pivoted to the remaining arm of the bell crank lever and carrying the movable contact, a spring urging said bell crank lever to move the lift rod to open circuit position, a second bell crank lever pivoted to said frame and having one arm below the joint of the toggle and its other arm depending across the remote end of one of said windings, a magnetic core in the last mentioned winding and connected to the depending arm of the second bell crank lever, and a resetting lever pivoted to the frame and provided with a pin for engaging the first lever to move the same to circuit closing position.

9. In an overload circuit breaker, a pair of axially alined and spaced magnet windings, circuit contacts between the adjacent ends of the windings, one of said contacts being fixed and a second of said contacts being movable transversely of the field between said windings, a frame magnetically connecting the remote ends of said windings, a lever having one end pivoted to the frame and projecting upwardly therefrom, a bell crank lever pivoted at its angle to said frame and having a depending arm, a pair of pivotally jointed links constituting a toggle, said toggle having its ends connected respectively to the first lever and the depending arms of the bell crank lever, a lift rod pivoted to the remaining arm of the bell crank lever and carrying the movable contact, a spring urging said bell crank lever to move the lift rod to open circuit position, means actuated by energization of said windings to engage and flex the toggle at its joint, said links being of equal length and the lever arms to which the ends of the toggle are connected being also of equal length, and a resetting lever pivoted to the frame and provided with a pin for engaging the first lever to move the same to circuit closing position.

10. In an overload circuit breaker, a pair of axially alined and spaced magnet windings, circuit contacts between the adjacent ends of the windings, one of said contacts being fixed and a second of said contacts being movable transversely of the field between said windings, a frame magnetically connecting the remote ends of said windings, a lever having one end pivoted to the frame and projecting upwardly therefrom, a bell crank lever pivoted at its angle to said frame and having a depending arm, a pair of pivotally jointed links constituting a toggle, said toggle having its ends connected respectively to the first lever and the depending arms of the bell crank lever, a lift rod pivoted to the remaining arm of the bell crank lever and carrying the movable contact, a spring urging said bell crank lever to move the lift rod to open circuit position, a second bell crank lever pivoted to said frame and having one arm below the joint of the toggle and its other arm depending across the remote end of one of said windings, a magnetic core in the last mentioned winding and connected to the depending arm of the second bell crank lever, and a resetting lever pivoted to the frame and provided with a pin for engaging the first lever to move the same to circuit closing position.

WILHELM LEYHAUSEN.
